RELEASE MECHANISM FOR STATIONARY
KNIVES OF SHREDDERS

John L. Aasland, Moline, Ill., assignor to International Harvester Company, a corporation of New Jersey

Application January 22, 1952, Serial No. 267,674

3 Claims. (Cl. 146—106)

1

This invention relates to a new and improved release mechanism for the stationary knife of a shredder.

Shredders such as used in the cutting up of corn stalks either in a green or dry condition, or for other similar materials, ordinarily employ a knife rotor which operates in combination with a stationary knife or shear plate to effect the cutting of these materials. Such shredders may be a part of a stationary machine or may be carried on a field-traversing corn picker or the like. In either location, however, it is necessary to supply the rotor with sufficient torque to enable the rotor to continue rotating during periods of great loads. The load imposed on such a shredding mechanism is more difficult to overcome at the time of starting than it is during periods of full speed operation of the rotor inasmuch as the rotor has considerable momentum.

It is, therefore, a principal object of this invention to provide means in association with a shredding mechanism to enable the rotor portion thereof to be started and attain full speed prior to the imposition of a heavier load thereon.

An important object of this invention is the provision of means in a shredding mechanism for hingedly mounting the stationary knife or shear plate thereof for regulating the spacing between the rotor and shear plate.

Another important object of this invention is to supply cam means for effecting an outward swinging of a shear plate in a shredder mechanism for the dual purpose of relieving the rotor of its load at the time of starting, and also to relieve and clean out the shredder mechanism at any time when the mechanism becomes jammed due to overloading.

Still another important object of this invention is to provide a hinged shear plate for a stalk shredder and in cooperation therewith cam means for accomplishing an outward swinging of the hinged shear plate and further the device having spring means for normally urging the cam means into a position corresponding to the cutting position of the shear plate.

Other and further important objects of this invention will become apparent from the disclosures in the following specification and accompanying drawings.

In the drawings:

Fig. 1 is a top plan view of the shredder mechanism of this invention.

Fig. 2 is a sectional view taken on the line 2—2 of Fig. 1.

2

Fig. 3 is a front elevational view of the device as shown in Fig. 1.

As shown in the drawing, the reference numeral 10 indicates generally a stationary tubular supporting member. As stated above, the shredder mechanism of this invention may represent a stationary unit or may be mounted on a movable corn picker for the purpose of shredding stalks after the ears of corn have been picked therefrom. The supporting member 10 thus may be considered to be either a part of the stationary framework of a stationary shredder or may be considered a part of the stationary framework of a field traversing corn picker, or the like. The tubular member 10 is expressly for the purpose of carrying a shear plate of the shredder mechanism which includes the cooperating rotating cutter 11. The rotor cutter 11 is mounted on a transversely disposed shaft 12 which is journally mounted for rotation in stationary frame members, not shown. The rotor cutter 11 includes radially extending arms 13, the outer ends of which are provided with knife blades 14. As shown, the blades 14 are riveted or otherwise fastened to the radial arms at 15. The blades 14 are provided with sharpened forward edges 16 which cooperate with a stationary shear plate 17, as best shown in Fig. 2, for effecting cutting of stalks or the like into short lengths.

The shear plate 17 is bolted, as shown at 18, to a C-shaped bracket member 19. The C-shaped bracket 19 extends down beneath the main frame member 10 and up around the rear side thereof. The C-member 19 carries a shaft 20 which is hingedly mounted within spaced-apart hinge brackets 21 and 22. Cotter pins 23 and 24 are adapted to pass through openings in the opposite ends of the hinge shaft 20, thus maintaining the shaft and its C-shaped bracket 19 in hinged relationship with respect to the spaced members 21 and 22.

The bracket members 21 and 22 are fixedly mounted with respect to the main tubular frame support 10. The attachment of the brackets 21 and 22 to the frame 10 is accomplished by means of welding, as shown at 25. In effect, the base portion of the brackets 21 and 22 shown at 26 constitute sleeves which encircle a substantial portion of the tubular member 10. The C-shaped bracket 19 thus is permitted swinging movement about the hinge shaft 20 to effect relative positioning of the stationary shear plate 17 with respect to the knife blades 14 of the rotary cutter 11.

55 The supporting brackets 21 and 22 are provided

with a bridge member 27 intermediate thereof and adjacent the sleeve-like base member 26. An adjustable screw 28 is adapted to engage a threaded aperture in the center thereof directly opposite the C-shaped bracket 19. Without other holding means the shear plate 17 and the C-shaped bracket 19 would fall to a position vertically spaced beneath the hinge shaft 20. Thus by means of the adjustable screw 28 the C-shaped bracket has its downward swinging position limited at any desired location and it is thus apparent that adjustment of the screw 28 may be employed to effect proper register of the knife edges 16 of the blades 14 with respect to the shearing knife 17.

As best shown in Fig. 2, the C-shaped bracket 19 includes an upper extension 29 on the back side of the supporting member 10 and located above the hinge pin 20. Lateral movement of the extension 29 toward and away from the stationary tubular member 10 will accomplish a swinging of the C-shaped bracket 19 about the hinge pin 20. A horizontally disposed bar 30 is slidably positioned between the tubular member 10 and the upward and rearward extension 29 of the C-shaped bracket 19. The bar 30 is provided with cammed notches 31 and 32 adjacent each of the spaced apart hinges. The length of the rotor 11 and the cooperating shear plate 17 may be any length desired and it should be understood that if the rotor and shear plate are relatively long they will require additional hinges to maintain suitable rigidity for the mounting of the shear plate. In the device as shown there are two spaced apart hinges 33 and 34. The hinge means 33 has heretofore been described in detail with the hinge pin 26 journally mounted within the spaced bracket arms 21 and 22. The construction of the spaced apart hinge 34 is identical to the hinge 33 and thus the parts thereof will not be redescribed. The cammed notches 31 and 32 of the bar 30 thus engage the upper extensions 29 of C-shaped brackets 19 and lateral movement of the bar 30 in the direction of the arrow 35 will cause the outward swinging of the upper portions 29 of the C-shaped brackets 19. This movement results in an upward positioning of the shear plate 17 as shown in the dash line position of the shear plate in Fig. 2. The cam notch 31 includes a relatively flat deep surface 36 and an inclined surface 37 extending from the deep surface 36 outwardly to the outer side 38 of the bar 30. When the upper extension 29 of the C-shaped bracket 19 is disposed within the cam notch 31 in the flat deep portion 36 the shear plate 17 is in operating relationship with respect to the rotary chopper 11; however, as the bar 30 is moved laterally the extension 29 rides up the inclined wall 37 causing the shear plate 17 to be swung upwardly away from its proximate relation with respect to the rotor knife blades 14.

The bar 30 is moved laterally by the actuating lever 39 which, as best shown in Fig. 3, is hinged at 40 to the side of the tubular frame 10. The lever arm 39 engages a notch 41 in the bar 30 and it is apparent that an operator may accomplish lateral shifting of the bar 30 merely by swinging the hand lever 39. A spring 42 is anchored at one end to a post 43 on the stationary tubular frame 10 and at its other end engages the end of the bar 30, as shown at 44. The spring 42 normally urges the bar 30 to the position as shown in Fig. 1 where the upward extensions 29 of the C-shaped brackets 19 are in their positions where-

in the shear plate 17 lies closely adjacent the knives 14 of the rotary chopper for causing stalks fed therethrough to be cut into short lengths.

In the operation of the present device the chopper 11 is rotatably driven in the direction as indicated by the arrow 45. The knives 14 on the peripheral surface of the rotor 11 pass around the cutter with the shear plate 17 to effect a cutting or chopping of corn stalks, or the like, which are fed through the juncture between the rotary chopper and the shear plate. When the device is put into operation it is desirable to permit the rotor 11 to attain its cutting speed before imposing a plurality of stalks thereon to be chopped. During this initial starting time the operator swings the lever arm 39 in the direction indicated by the arrow 46, in Fig. 3, causing the bar 30 with its spaced cammed notches 31 and 32 to be moved laterally and to thus swing the upward extensions 29 of the C-shaped brackets 19 outwardly away from the stationary tubular frame 10 causing the shear plate 17 to be materially spaced from the rotor 11. The stalks which are fed to the rotor during this starting time are, of course, not cut but immediately upon the rotor 11 attaining its cutting speed the hand lever is returned to its initial position as shown in full lines in Fig. 3, and the shear plate 17 is simultaneously returned to its cutting relation with respect to the rotor. The operator is assisted in returning the hand lever 39 to its "home" position by reason of the assisting spring 42. The "home" position of the shear plate 17 is regulated by the adjusting screw 28. Immediately upon the shear plate 17 being moved down into cutting relationship the stalks passing therethrough are chopped into small pieces. It is obvious that the starting of the rotor 11 with the shear plate 17 spaced therefrom saves the power unit, not shown, from becoming overloaded. Further it eliminates the necessity of employing an excessively large power unit which would be necessary if the rotor 11 had to be started under full load. The mass of the rotary chopper 11 is sufficient so that its momentum carries it through the majority of load imposed thereon. However, in the event the shredder mechanism becomes clogged or jammed after commencing operation the shredder may be conveniently cleaned out by merely shifting the hand lever 39 in the same manner as done before the shredder is put into operation.

Numerous details of construction may be varied throughout a wide range without departing from the principles disclosed herein and I therefore do not propose limiting the patent granted hereon otherwise than as necessitated by the appended claims.

What is claimed is:

1. A stalk shredder comprising a supporting structure, a cutting rotor rotatably carried on said supporting structure, a supporting bar forming part of said supporting structure, hinge means fastened on one side of said bar, a C-shaped bracket having a hinge pin associated with said hinge means and constituting a hinge, said C-shaped bracket extending down around the underside of said supporting bar and thence upwardly on the other side thereof, a shear plate affixed to the end of the C-shaped bracket away from said hinge, and means effecting swinging of said C-shaped bracket about said hinge, said means including an extension of said C-shaped bracket to the other side of said hinge, a slidably 75 bar positioned intermediate said extension and

said supporting bar, and cam means on said slideable bar adjacent said hinge for causing swinging of said C-shaped bracket about said hinge upwardly away from said cutting rotor.

2. A device as set forth in claim 1 in which a hand lever is pivotally mounted on said supporting bar, and said slideable bar having a notch therein for receiving said pivoted hand lever, whereby swinging of said hand lever effects swinging movement of said shear plate away from said cutting rotor.

3. A device as set forth in claim 2 in which

spring means is fastened to said supporting bar and to said slideable bar for normally urging said shear plate into cutting relationship with said cutting rotor.
